FISHING LINE GUIDE

Thomas E. Coalson, 15182 Warwick Circle,
Westminster, Calif. 92683

Filed May 28, 1970, Ser. No. 23,183

Term of patent 14 years

Int. Cl. D22—08

U.S. Cl. D22—24

FIG. 1 is a perspective view of the fishing line guide;
FIG. 2 is a side elevation view of the fishing line guide
of FIG. 1; and

FIG. 3 is a front elevation view of the fishing line guide
of FIG. 1.

I claim:

The ornamental design for a fishing line guide, substantially as shown.
